INVENTOR

UNITED STATES PATENT OFFICE.

JESSE C. MARTIN, JR., OF SAN FRANCISCO, CALIFORNIA.

REFRACTORY-BRICK CONSTRUCTION FOR LOCOMOTIVE-BOILER FURNACES.

1,333,868.

Specification of Letters Patent. Patented Mar. 16, 1920.

Application filed October 17, 1919. Serial No. 331,372.

To all whom it may concern:

Be it known that I, JESSE C. MARTIN, Jr., a citizen of the United States, and a resident of San Francisco, county of San Francisco, and State of California, have invented certain new and useful Improvements in Refractory-Brick Construction for Locomotive-Boiler Furnaces.

The hereinafter described invention relates to the burning of hydro-carbon fuel in locomotive fire boxes wherein refractory lining is required to prevent burning out of the exposed steel surfaces of the fire box combustion chamber.

It is an object of the invention to place a hollow refractory brick structure at the front end of the fire box adjacent the tube sheet thereof through which all of the air required to be introduced into the front of the fire box for combustion purposes will be taken and to make the hollow brick structure of such length that, when it is set in place, it will extend rearwardly into the fire box sufficiently so that it will be thoroughly heated by the hot furnace gases, and air taken therethrough from the atmosphere at normal temperature, or cold air, will be heated and prevented from striking the tube sheet and exposed fire box sheets and seams, causing rapid expansion and contraction and consequently leakage, which, in locomotive practice, wherein the use of my invention is amplified, means excessive cost for fire box and boiler maintenance, short life of metallic heating surfaces, and consequent loss of motive power in service.

Another object of the invention is to effect fuel economy by delivering air required at the front end of the fire box for combustion purposes through a hollow refractory brick structure heated by the furnace gases, thereby heating the air and causing a lesser amount of oxygen for combustion to be required than when cold or normal temperature air is delivered into the fire box combustion chamber.

A further object of the invention is to make a hollow refractory fire brick or tile structure through which all of the hydro-carbon fuel injected into the fire box from the burner and all of the air required for combustion at the burner end of the fire box

will be taken, thereby effecting an intermingling of fuel and air through the outlet of the tile structure into the fire box combustion chamber and increasing the thermal efficiency therein.

Another object of the invention is to provide in a refractory lined hydro-carbon fuel burning locomotive fire box, a hollow refractory brick structure extending into the fire box at the front end thereof, through which air, or fuel and air, are delivered into the fire box combustion chamber, and which will be substantially supported in place against jar and vibration of locomotive road service by the bottom refractory brick floor of the fire box combustion chamber and the refractory brick end wall thereof.

In the accompanying drawings, Figure 1 is a sectional elevation of my hollow refractory brick structure set in place in a refractory brick lined locomotive fire box.

Fig. 2 is an end sectional view taken on line 2—2, Fig. 1.

Fig. 3 is a perspective view of the hollow refractory brick structure removed from the fire box.

Fig. 4 is an end view of a modified form of the hollow refractory brick structure.

Numeral 1 indicates a front end fired hydro-carbon burning refractory brick lined locomotive fire box combustion chamber of practice. Numeral 2 indicates one form of the hollow refractory brick structure set in the bottom of the pan between the refractory brick end wall, 3, and the refractory brick bottom, 4, being positioned against wall, 3, by guide, 5. Numeral 6 is a hydro-carbon burner set to discharge through hollow brick, 2, and 7 is a damper door for admitting air through hollow brick, 2, into the combustion chamber, 1. Numeral 8 indicates the lower rows of fire box tubes and 9 the exposed fire box sheets, while the calking or tight seams are shown at 10.

It is within the scope of my invention to build the hollow refractory brick structure of one or more units to best suit the local conditions of application and the dimensions of the brick may be such as will best suit and house the spray or jet of hydro-

carbon fuel injected into the fire box there-through, and in some fire pans forming the bottom of the fire box, the hollow brick may be constructed with unit members corresponding to the shape of the pan, for example, such as illustrated in Fig. 4.

In order to minimize the cost of manufacture and maintenance in service, as well as to better effect a close mixture and control of air and hydro-carbon fuel there-through, the roof of the hollow refractory structure can be made to set well below the top of the refractory end wall.

In practice the hollow refractory brick is highly heated by the hot furnace gases so that when atmospheric air is taken through damper door, 7, into the fire box combustion chamber, 1, the air is heated to a relatively high degree and cold air is entirely prevented from striking the exposed tubes, 8, sheets, 9, and seams, 10, of the fire box, as at present, which causes excessive leakage, expensive maintenance and rapid deterioration of fire box with locomotives out of service as a consequence, and in addition thereto, the leakage onto the highly heated refractory bricks causes rapid expansion and contraction which cracks and destroys the bricks causing expensive maintenance of same.

What I claim is:

1. In a refractory lined locomotive fire box, a hollow refractory brick constructed of unit members positioned by and extending rearwardly of the refractory front wall thereof and held in place therein by the bottom refractory floor of the fire box whereby an air passage is provided through the brick into the fire box combustion chamber.

2. In a refractory lined locomotive fire box, a hollow refractory brick constructed of unit members abutting and extending rearwardly of the refractory front wall thereof, said brick being supported on the bottom floor of the firebox and held in place therein intermediate the refractory front wall and refractory bottom floor of the fire box whereby an air passage is provided through the brick into the fire box combustion chamber.

3. In a refractory lined locomotive fire box, a hollow refractory brick constructed of unit members positioned by and extending rearwardly of the refractory front wall thereof, said brick being supported on the bottom of the fire box and held in place therein by the bottom refractory floor of the fire box, a damper door communicating with the hollow brick whereby an air passage controlled by the damper door is provided through the brick into the fire box combustion chamber.

4. In a refractory lined locomotive fire box, a hollow refractory brick constructed

of unit members abutting and extending rearwardly of the refractory front wall thereof, said brick being supported on the bottom floor of the fire box and held in place therein intermediate the refractory front wall and refractory bottom floor of the fire box, a damper door communicating with the hollow brick whereby an air passage controlled by the damper door is provided through the brick into the fire box combustion chamber.

5. In a refractory lined locomotive fire box, a hollow refractory brick constructed of unit members positioned by and extending rearwardly of the refractory front wall thereof, said brick being supported on the bottom of the fire box and held in place therein by the bottom refractory floor of the fire box, a damper door communicating with the hollow brick and a hydro-carbon burner set to discharge within the hollow brick whereby air through the damper door and hydro-carbon fuel from the burner are delivered through the hollow brick into the fire box combustion chamber.

6. In a refractory lined locomotive fire box, a hollow refractory brick constructed of unit members abutting and extending rearwardly of the refractory front wall thereof, said brick being supported on the bottom floor of the fire box and held in place therein intermediate the refractory front wall and refractory bottom floor of the fire box, a damper door communicating with the hollow brick and a hydro-carbon burner set to discharge within the hollow brick whereby air through the damper door and hydro-carbon fuel from the burner are delivered through the hollow brick into the fire box combustion chamber.

7. In combination, a locomotive firebox, a fire pan secured to the mud ring of the firebox, a hollow refractory structure composed of bottom, side and arched roof bricks supported within the fire pan to extend rearwardly of the refractory front wall thereof, a damper communicating with the hollow refractory structure and a hydro-carbon burner set to discharge within the hollow refractory structure whereby an air passage controlled by the damper is provided through the refractory structure and whereby hydro-carbon fuel from the burner is delivered through the refractory structure into the firebox combustion chamber.

8. In combination, a locomotive firebox, a fire pan secured to the mud ring of the firebox, a hollow refractory structure composed of bottom, side and arched roof bricks supported within the fire pan to extend rearwardly of the refractory front wall thereof, the side brick being fitted to the inclination of the fire pan sides and the arch brick being fitted against the side brick, a damper

communicating with the hollow refractory structure and a hydro-carbon burner set to discharge within the hollow refractory structure whereby an air passage controlled by the damper is provided through the refractory structure and whereby hydro-carbon fuel from the burner is delivered through

the refractory structure into the firebox combustion chamber.
